ATTORNEY

UNITED STATES PATENT OFFICE.

ARTHUR C. BARRETT, OF STOCKTON, CALIFORNIA.

WRENCH.

1,295,838.

Specification of Letters Patent.

Patented Mar. 4, 1919.

Application filed March 11, 1918. Serial No. 221,683.

To all whom it may concern:

Be it known that I, ARTHUR C. BARRETT, a citizen of the United States of America, residing at Stockton, in the county of San Joaquin, State of California, have invented certain new and useful Improvements in Wrenches; and I do declare the following to be a clear, full, and exact description of the same, reference being had to the accompanying drawings, and to the characters of reference marked thereon, which form a part of this application.

This invention relates to improvements in wrenches, particularly to that type commonly known as a monkey wrench. The object of the invention is to obviate the use of the now common advancing worms or screws used to drive the movable jaw of the wrench in one direction or the other. It is a slow, tedious job to move the jaw with such worm or screw and when the wrench is being used on nuts which are in more or less inaccessible places, it is very hard to adjust the jaws accurately without continually placing the wrench into and out of engagement with the nut for a number of times.

By the use of my improved invention, the movable jaw may be quickly and easily moved in either direction with a simple pressure of the thumb, and, when fixed against the nut, it can be instantly locked in that position and the wrench then operated at will. Thus, when a nut is in an inaccessible place, the fixed jaw may be fixed against one side thereof and the movable jaw immediately pressed into engagement with the opposite side of the nut. This will require but one positioning of the wrench.

The advantages of this will be obvious to those skilled in the art.

The use of my improved wrench also has many other advantages which will be recognized by those who are familiar with the use of the now common monkey wrench.

A further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claim.

On the drawings, similar characters of reference indicate corresponding parts in the several views.

Figure 1 is a side elevation of the complete wrench.

Fig. 2 is an edge view of the same.

Fig. 3 is a fragmentary view, in section, of the adjustment mechanism.

Fig. 4 is a cross-section through the shank of the wrench taken on a line 4—4 of Fig. 1.

Referring now more particularly to the characters of reference on the drawings, the numeral 1 designates the shank, on the end 65 of which is the fixed cross-head or jaw 2. Each side of the shank 1 is provided with a longitudinal groove 3 which acts as a guide for a flanged retainer and brace 4 mounted on the slidable jaw 5. This jaw 5 is also 70 provided with a retaining strap 6 which encircles the shank 1.

The inner edge of the shank 1 is provided with a longitudinal groove 7 provided for a portion of its length with bottom ratchets 75

The slidable jaw 5 is provided with a projecting bracket 9 which is bifurcated, as at 9^a, to pivotally receive a finger member 10 on a ratchet dog 11 adapted to engage the ratchet teeth 8. This finger member projects 80 underneath the bracket 9 and is provided at one point with a pin 12 which projects through said bracket and which is provided with a thumb button 13. A spring 14 normally engages the under side of the finger 85 member 10 to hold the dog 11 in engagement with such ratchet teeth 8. When in this position, the movable jaw 5 is held against movement. When it is desired, however, to move such jaw one way or the other to fit 90 different sized nuts, the shank 1 is held in the hands of the operator and the thumb button 13 pressed downwardly. This moves the finger member 10 against the spring 14 and releases the dog 11 from the ratchets 8. 95

The jaw 5 may then be freely slipped along in either direction. When the desired position thereof is reached, the thumb button 13 is released and the spring 14 presses the dog 11 into engagement with one of the ratchets 100 8, whereupon the wrench may be used to perform its function.

The dog 11 engages the ratchets 8 at such an angle that the pressure against the same drives such dog directly against the bottom 105 of the ratchets. Thus, there is no tendency to wear out the ratchets, but instead thereof, they will tend to be made deeper. Any sheering strain against the pin 10^a, by means of which the finger member 10 is pivoted 110

within the bifurcated portion 9^a of the bracket 9, is overcome by having a concentric bearing relation between the dog 11 and the ends of the members 9^a, as at 10^b. Thus 5 the pressure occasioned by the use of the ratchets will not come on the pin 10^a but will come directly against the bracket 9 and dog 11 and the shank 1 by reason of the engagement of the dog 11 with the ratchets 8.

10 From the foregoing description it will readily be seen that I have produced such a device as substantially fulfills the objects of the invention as set forth herein.

15 While this specification sets forth in detail the present and preferred construction of the device, still in practice, such deviations from such detail may be resorted to as do not form a departure from the spirit of the invention, as defined by the appended claim.

20 Having thus described my invention, what I claim as new and useful and desire to secure by Letters Patent is:—

25 A wrench comprising a shank, a fixed jaw and a slidable jaw, said shank being provided with a longitudinal groove on each side, a guide member on the slidable jaw slidable in the grooves, the shank being further provided with a longitudinal slot in its

inner edge, ratchets formed in the bottom of the slot, a downwardly extending bracket 30 on the slidable jaw, a spring pressed finger member pivoted at one end in the bracket and positioned between the bracket and the slot and having a projecting lug impinging against the lower end of the bracket, a dog 35 pivoted to the finger member normally projecting into the slot and engaging the ratchets at an acute angle therewith to hold the slidable jaw against movement away from the fixed jaw, means in the bracket for engaging the finger member to lift the dog 40 from the ratchets, the dog being provided with recesses on each side frictionally engaging with the end of the finger member whereby the compressive strain on the slidable jaw and the finger member and dog 45 thereof is distributed evenly throughout and is not concentrated at the pivotal point of the dog and finger members.

50 In testimony whereof I affix my signature in presence of two witnesses.

ARTHUR C. BARRETT.
